(57) **CLAIM**

The ornamental design for a wall-mounted air conditioner, as shown and described.

DESCRIPTION

This application claims subject matter that is related to that shown in co-pending U.S. application Ser. No. 29/287,245, filed concurrently herewith, and claiming the benefit of Korean Patent Application Serial No. 30-2006-0002269, filed Jan. 17, 2007.

FIG. 1 is a perspective view of a wall-mounted air conditioner;

FIG. 2 is a front view of the wall-mounted air conditioner of FIG. 1;

FIG. 3 is a rear view of the wall-mounted air conditioner of FIG. 1;

FIG. 4 is a left-side view of the wall-mounted air conditioner of FIG. 1;

FIG. 5 is a right-side view of the wall-mounted air conditioner of FIG. 1;

FIG. 6 is a top plan view of the wall-mounted air conditioner of FIG. 1; and,

FIG. 7 is a bottom plan view of the wall-mounted air conditioner of FIG. 1.
